FOOT ADJUSTER

Kenneth B. Whitney, Toronto, Ontario,
CanadaApplication May 15, 1937, Serial No. 142,912
In Canada April 12, 1937

7 Claims. (Cl. 128—69)

This invention relates to a foot adjuster and particularly that type of appliance for treating weak or fallen arches.

In the science of treating feet it is generally recognized that many ailments, some obscure, are attributable to weak or fallen arches and that when the feet are adjusted to proper condition, the delicate nervous system of the anatomy effected by reflex action becomes normal and the complaints removed.

With the present invention, complete home treatment of the feet is contemplated wherein the plantar, transverse and anterior arches may be gently articulated and treated so that the flaccid muscles and tendons of the feet become strengthened, nerve pressure relieved and such bones as the cuboid, cuneiform, metatarsal, etc., again adjusted, thus with renewed strength, flexibility of muscle, increased circulation, limber action of the pedal digits, etc., the feet are restored to normal and general health materially improved.

One of the objects of the present invention therefore is to provide a device of this character wherein foot weakness or fallen arches may be effectively treated.

Another object of the present invention is to provide a device of this character wherein the feet of the individual are placed in such a position that it causes the person to relax otherwise taut muscles during treatment or adjustment of the arches.

A further object of the present invention is to provide a device of this character wherein the muscles of the feet are strengthened, corrective articulation applied, circulation stimulated and the feet generally restored to a healthy condition.

Yet a further object of the present invention is to provide an appliance of this character in which the arch treating elements may be adjusted to meet the requirements of various conditions.

Having regard to the foregoing and other objects and advantages which will become known as the description and nature of the invention become known, the invention consists essentially in the novel combination and arrangement of elements and parts hereinafter described in detail and illustrated in the accompanying drawing in which:

Fig. 1 is a plan view of an embodiment of the invention, the dotted lines showing representations of feet in arch treating position.

Fig. 2 is a side elevation of Fig. 1.

Fig. 3 is an end view of the apparatus shown in Fig. 1, the dotted lines showing a bowing of the pedal extremities during treatment.

Fig. 4 is a detail of the adjustable exerciser for the anterior arch.

Fig. 5 is a view of a modified type of arch treating member, and

Fig. 6 is a view of an adjustable type of arch treating member.

Referring now to the drawing wherein like letters and numerals designate corresponding parts in the several illustrations, the letter A indicates the appliance as a whole which includes the plantar and transverse arch treating member B and the anterior arch treating member C.

In a general way the structure of the apparatus consists of a base 10 provided with a foot receiving platform 11 which is composed of angularly disposed or slopingly arranged foot receiving surfaces 12 and 13 corresponding substantially to an inverted V formation.

At the base of the foot receiving surfaces I provide foot bracing or abutting walls 14 and 15 which in combination define substantially V-shaped channel like formations 16 and 17 to guard the foot position while associated with the foot receiving platform and preferably arranged in a horizontal plane is the treating member C. The base and platform structure may be formed separately, or, as is well known in the art, may be stamped or moulded from suitable materials in unit form.

In practice, the surfaces of the appliance contacted by the feet are preferably provided with a covering of material 18 such for example as rubber so that the slipping of the feet of the individual may be guarded against during adjustment of the feet.

Coming now to an essential feature of the invention, this comprises an elongated rib member 19 formed with a flat base and rounded upper portions. In structure the rib member is relatively hard but with somewhat flexible properties and diminishes in thickness toward its extremities while extending from side to side over the angularly disposed surfaces of the platform 11. By particular reference to Fig. 3 it will be observed that the member 19 is distinctly thick at the apex or crown of the platform and in a curved manner gradually diminishes to an almost inconsequential thickness at the channels 16 and 17. In location, the member 19 is positioned substantially midway of the length of the platform at a point where there is ample space for movement of the feet forward and backward.

on the platform as will be hereinafter referred to.

As particularly illustrated in Figs. 1 to 3 inclusive, the member 19 is disclosed as being formed integral with the covering of the platform however it will be understood that the detachable and adjustable types shown in Figs. 5 and 6, later described in detail, may be employed.

A further and essential feature of the present invention is the angle or sloping arrangement of the foot receiving surfaces 12 and 13. One of the important purposes served by such arrangement is that it induces the individual to stand in a straddling position, the sloping surfaces naturally turning the feet sideways and causing a bowing of the legs such bowing in turn causing a relaxation of muscles and with muscles relaxed the treatment of the feet is more effective, thorough and efficient. A definite angle or slope for the foot receiving surfaces is not established however it may be said that an angle of forty degrees has been found to be practical for the majority of cases, it being understood nevertheless that the angle of the foot receiving surfaces may be varied within the purview of the invention.

Referring now to the member C which is designed for the treatment of the anterior arch, this also comprises a rib member which is indicated by the numeral 20. In general terms the member 20 is substantially arcuate in form and composed of relatively hard yet somewhat resilient material. As observed, the member 20 is also rounded on the upper surfaces and may either be formed integral with the covering 18 or as is indicated in Fig. 4, may be adjustable so that the height may be varied as desired. In its adjustability the components include a threaded rod 21 operable by a wing nut or the like 22, the rod threadedly engaging plate 23 and extending into a socket 24 which in turn is secured to a plate 25 which further in turn is embedded in the member 20. From the foregoing it will be obvious that operation of the nut 22 will cause the member 20 to move upwardly or downwardly to a protruding position best suited to individual needs and requirements.

Reverting now to the transverse rib member 19 previously mentioned and especially the detachable type shown in Fig. 5, this comprises a separately formed rib member having a wire or rod 26 extending therethrough, the ends of the rod being secured beneath the platform surfaces by nuts 27 or other suitable securing means. In the adjustable and detachable rib disclosed in Fig. 6, an elongated wedge like member 28 is adapted to be inserted between the base of the rib proper and the faces of the platforms 12 and 13. The extremities of the wedge member and of the rib member are detachably secured in position by means of bolts or similar securing means 29. For illustrative purposes I have shown only one size of wedge member, it is self evident however that a series of wedges of various tapers and thicknesses may be provided to vary the extent of the protrusion of the rib member as may be required or desirable to suit differing conditions and circumstances with respect to the feet requiring treatment.

In addition to the foregoing I provide means for elevating what may be termed the front end of the apparatus. This may be accomplished in any convenient form and I have shown threadedly engaged leg members 30 which may be extended to elevate one end of the apparatus as

desired. One of the purposes served in elevating one end of the apparatus is that it enables treatment to be correctively effected with a double angle in certain instances than when applied normally in accordance with the invention.

When arch treatment is to be effected, the individual stands in an upright position with both feet placed upon the angularly disposed foot receiving surfaces 12 and 13, the arches of the feet resting upon the rib member 19 with the outside of the feet in the channel arrangement abutting the guard walls 14 and 15 (see Fig. 3).

In the posture just described, the sloping arrangement of the surfaces 12 and 13 will, as previously mentioned, cause a bowing of the legs and in consequence thereof muscle relaxation. With the full weight of the body upon the pedal extremities, the rib member 19 fits neatly into the transverse arch portions of the feet. Very minute steps are then taken by the individual in a forward and backward direction until the entire plantar and transverse arches have been subjected to treatment during which the bones, muscles, ligaments, etc., of the feet exercised and manipulated. With this treatment completed the individual then steps off the sloping surfaces and takes up a position at the opposing end of the apparatus. As previously mentioned the appliance C is designed for the treatment of the anterior arch and corrective treatment of this arch is effected by placing one of the feet in the position indicated by dotted lines in Fig. 1 with the member 20 extending between the toes from which position the leg is then bent forward as indicated in dotted lines at 31 in Fig. 2. This exercise and adjustment is further repeated until the entire anterior arch of both feet have been correctively exercised.

From the foregoing it will be seen that by my novel arrangement, manipulation and exercise may be administered to the various arches, bones and muscles of the feet under most favorable application of restoring pressure and corrective articulation which revives and strengthens flaccid muscles, relieves tension and stimulates blood circulation all of which is conducive of improved health.

Many changes may be made in the above and many apparently widely different embodiments constructed without departing from the spirit or scope of the invention. It is intended therefore that all matter herein related shall be interpreted within the scope of the claims.

What I claim as my invention is:

1. In a structure of the character described, a base member having two substantially flat foot receiving surfaces sloping outwardly and downwardly from a middle ridge adapted to support the length of the feet with the feet inclined outwardly, and an elongated rib member extending transversely across and protruding above the flat foot receiving surfaces adapted to elevate the instep arch.

2. In a structure of the character described, a foot receiving platform having two substantially flat foot receiving surfaces sloping on an appreciable incline outwardly and downwardly from a middle ridge, an elongated rib member extending transversely across the foot receiving surfaces intermediate the ends thereof and protruding above the flat foot receiving surfaces and shaped to present a substantially wedge-shaped rib portion in the middle area of each foot receiving surface with the thickened end of the

- wedge-shaped form at the ridge, and means to vary the elevation of parts of said rib above the foot receiving surfaces.
3. In a structure of the character described, a base member having an elongated ridge in the middle portion thereof with individual foot receiving surfaces sloping at an appreciable angle outwardly and downwardly from said ridge, and an elongated rib member detachably and replaceably located across the ridge to extend transversely over each foot receiving surface on the side adjacent to the ridge.
4. In a structure of the character described, a base member having a medial ridge with two substantially flat foot receiving portions sloping appreciably outwardly and downwardly from the ridge, and an elongated rib member fitted transversely across said base provided with a flat under face to fit and extend from the ridge laterally down onto and over a part of each foot receiving surface and having its upper side rounded transversely and reduced in thickness toward the ends whereby the rib member is characterized in an arcuate formation.
5. In a structure of the character described, a base member having a longitudinal ridge with foot receiving surfaces sloping outwardly and downwardly at an appreciable angle on each side of the ridge, foot bracing or abutting walls at the outer edge of each of the foot receiving surfaces, and an elongated rib member detachably fitted upon said base member and extending

transversely over the side of each foot receiving surface adjacent to the ridge, the said rib member being rounded in transverse formation and having greater thickness toward the ridge and lesser thickness toward the foot bracing walls.

6. In a structure of the character described, a base member having two substantially flat foot receiving surfaces sloping outwardly and downwardly from a middle ridge, an elongated rib member extending transversely across and protruding above the flat foot receiving surfaces, said base member being adapted to be supported as upon a floor whereby the user may stand with one foot on each of the foot receiving surfaces, and means to tilt and adjust the disposition of the base member as an entirety with respect to the floor.

7. In a structure of the character described, a base member of the stationary type provided with a medial ridge and two substantially flat foot receiving surfaces sloping downwardly and outwardly from the said ridge at an angle of appreciable inclination, an elongated rib member extending transversely across the foot receiving surfaces substantially intermediate their ends and protruding above the said foot receiving surfaces, the said rib member being of substantially wedge-shaped formation characterized by a thickness that is greater toward the medial ridge and a lesser thickness toward the outer edges of the foot receiving surfaces.
